COOLING COIL FOR REFRIGERATORS

Filed April 11, 1930

Fig. 1.

UNITED STATES PATENT OFFICE

WILLIAM SLOAN, OF EAGLEVILLE, PENNSYLVANIA

COOLING COIL FOR REFRIGERATORS

Application filed April 11, 1930. Serial No. 443,497.

The object of the invention is to provide improvement in cooling coils and especially in means for adapting such coils to the ordinary household refrigerator.

- 5 Another object is to provide a coil of tubing in combination with means for maintaining the convolutions of such coil in a plane, so that the coil as a unit will fit closely against an inner wall surface of a refrigerator.
- 10 A further object is to provide a system whereby such coil may be operatively mounted and connected with one or more extraneous sources of water supply and with a discharge valve also upon the outside of a refrigerator.

15 Still another object is to provide an improved receptacle, operative to receive the neck of and support in inverted position a bottle of liquid, adapted to discharge its contents through said receptacle into said coil, and to provide means for operatively securing such receptacle to the top refrigerator wall.

20 With these and other objects in mind, the present invention comprises further details of construction and operation which will be fully brought out in the following description when read in conjunction with the accompanying drawings, in which Fig. 1 is a perspective view of a cabinet representing a refrigerator and showing one embodiment of the invention operatively mounted in association therewith; Fig. 2 is an enlarged fragmentary vertical section through the supporting receptacle for an inverted bottle of water or other liquid; Fig. 3 is an enlarged fragmentary vertical section of the cooling coil and left-hand wall of the cabinet as viewed in Fig. 1; Fig. 4 is a similar section of a portion of the same wall taken on a plane in front of the plane of Fig. 3 and showing the discharge end of the coil and hand operated valve; and Fig. 5 is a central irregular horizontal section through the coil per se.

25 Referring to the drawings, the cabinet of Fig. 1 will be referred to as a refrigerator and comprises a top wall mounted upon laterally opposite side walls 2 and 3 and upon a rear wall 4, while the front wall 5 of the device is provided with an opening 6 which is nor-

mally closed by means of a suitably mounted door 7, a bottom wall 8 closing the lower portion of the interior of such refrigerator. Each of these walls and door it is to be understood are of any suitable cross sectional structure, but in general comprise relatively outer and inner spaced wall casings 9 and 10, separated by any suitable form of heat insulating material 11.

30 Through the top wall 1 is drilled a bore 12, through which is passed one end 13 of a tube, the lower end 14 of which is deflected angularly and provided with a coupling 15. Upon the outer surface of said top wall is secured a plate 16 by any suitable means 17, to said plate in turn being welded or otherwise unitarily secured the bottom 18 of a receptacle, which also comprises upwardly extending flared or bell-shaped walls 19, the outer periphery 20 of which is provided with a continuous groove 21 in which is positioned a gasket 22, against which rests the neck portion 23 of a bottle 24 containing water or other liquid, the terminal portion 25 of the bottle neck 23 fitting loosely within the lower portion of said receptacle, while the continuity of the gasket 22 is broken at one or more points 26, to provide air vents for the admission of air to the interior of the bottle 24 as the contents of the same flow therefrom. The 35 plate 16 and bottom 18 of said bottle receptacle are provided with aligned apertures 27, through which extends the upper portion 13 of said tube, and which upper portion above the inner surface of said receptacle bottom 40 wall is flared and soldered or welded at 28 to said receptacle wall to make a liquid-tight joint.

45 Formed inside of the refrigerator is a coil 29 of tubing of any desired number of convolutions which preferably lie in a single plane, and are secured therein and in equal spaced relation with respect to one another by means of oppositely positioned bars 30, secured together as shown in Fig. 5 by any 45 suitable means 31. The inner end 32 of said coil is connected through an L 33 and nipple 34 to a T 35, whence a nipple 36 connects said T to a valve 37, in turn connected through the medium of a tube 38 with the coupling 15. 100

That end of the T 35 opposite to the nipple shaped receptacle adapted to receive the neck 34 is connected by way of another nipple 39 to a valve 40 and thence through a nipple 41 to a coupling 42, the opposite side of which is connected to the inner end 43 of a pipe 5 which extends through the rear wall 4 of the refrigerator and is connected thereto by any suitable air sealing medium, such as rubber, said pipe upon the outer side and to the rear 10 of the refrigerator passing along the path indicated by the dotted lines 44 and being provided with a coupling 45, by means of which this pipe is adapted to be connected to a continuous fresh water supply from any desired source.

15 The opposite end 46 of the coil 29 is provided with an L 47 which is connected through the medium of a nipple 48 with any suitable type of faucet 49 upon the outside of the 20 refrigerator, said nipple 48 passing through the adjacent wall of the latter and an airtight connection therewith being insured by means of the gaskets 50. For convenience, the outer surface of the faucet-supporting 25 wall may be provided with a suitable bracket 51, upon which may rest a drinking receptacle or glass 52. Within the refrigerator the side walls are provided with any suitable form of brackets 53, which removably support shelves 54 of any suitable construction 30 and number.

In the operation of this device, it will be noted primarily that the coil 29 comprises a unit which may be inserted into and removed 35 from within a refrigerator at all times as a unit, and the weight of which in operation is preferably supported directly by the bottom wall 8. After connecting the ends 32 and 46 of the coil to the various couplings 40 as hereinbefore described, and after inverting a bottle of water or other liquid as shown in Figs. 1 and 2, so that its contents may flow 45 freely into the receptacle 19, the contents of this bottle may be permitted to pass through the cooling coil and taken therefrom upon and by means of actuations of the faucet 49, after opening the valve 37 and closing the valve 40. On the other hand, if water from a 50 constant source is desired through the pipe indicated at 44, the valve 37 is closed and the valve 40 opened, whereupon this water may flow through said coil and be drawn 55 therefrom through said faucet as desired.

However, while various pipe connections 60 have been herein described in detail, various alterations therein and in details of construction of the coil and its associated elements may be made without departing from the scope of the invention as defined by the appended claims.

Having thus described my invention, what I claim and desire to protect by Letters Patent of the United States is:—

65 The combination of a cabinet having a top wall provided with a bore, an inverted bell-

70 of and support a bottle in inverted position, an annular gasket carried by and adjacent to the free edge portion of said receptacle to cushion a bottle with respect thereto, a tube 75 extending from within said receptacle through said bore and into said cabinet, a planar coil of concentric convolutions of tubing supported upon one end parallel with and adjacent to the inner surface of a side 80 wall of said cabinet, tubular means connecting one end of said coil to said tube, a discharge valve connected to the opposite end of said coil, a valve in said tubular means, a second tubular means connecting said first 85 end of said coil to a second source of liquid, and a valve in said second tubular means, said valves in said tubular means being adjustable to operatively connect said coil either to said receptacle or to said second source.

In testimony whereof I have affixed my signature.

WILLIAM SLOAN.
